United States Patent Office

Des. 229,491

Patented Dec. 4, 1973

229,491

RACING VEHICLE

Craig N. Breedlove, 2412 Amsler St.,
Torrance, Calif. 91305

Filed Jan. 7, 1972, Ser. No. 216,340

Term of patent 14 years

Int. Cl. D12—08

U.S. Cl. D12—85

FIG. 1

FIG. 3

FIG. 2

FIG. 1 is a perspective view of a racing vehicle showing my new design;

FIG. 2 is a front elevational view thereof;

FIG. 3 is a rear elevational view thereof;

FIG. 4 is a top plan view thereof; and

FIG. 5 is a right side elevational view, the left side being substantially a mirror image thereof.

I claim:

The ornamental design for a racing vehicle, substantially as shown and described.
